AMUSEMENT DEVICE

Roger L. Carwile, Cambridge, Mass.

Application February 25, 1947, Serial No. 730,715

5 Claims. (Cl. 46—1)

1

The present invention relates to a device which may serve as a means for demonstrating the action of certain physical phenomena, or in other capacities, as a toy for instance, or as a means for producing certain physical action where desired. Essentially, the device produces a physical action or motion which, while simple, is difficult for the eye to follow and causes an optical illusion which is mysterious and therefore engages the interest of the observer, whether adult or child.

The physical principle involved is akin to that demonstrated by two free pendulums, suspended side by side, having highly elastic balls such as ivory, of equal mass. If one pendulum is swung so that the moving ball strikes the stationary one at the bottom of its stroke, the first ball will stop and the second will move, assuming substantially the velocity of the first ball. In the present invention, two or more flat, perforated, thin plate or disc-like members are used. These perforated thin plates or discs slide over a guide wire in such a way that substantially the full velocity of one will be imparted to a stationary plate or disc at a certain place in its course of motion over the guide wire where the stationary plate or disc is positioned. A series of pairs or groups may be used in such a manner that a succession of operations of similar or different motions and effects may be obtained.

The present invention will be more fully described in the specification below, in connection with the drawings illustrating the same, in which Fig. 1 shows a perspective drawing of the invention in one form. Fig. 2 shows a sectional elevation of the form of Fig. 1, and Figs. 3 and 4 show modified forms of the invention of Fig. 1.

In the embodiment of the invention shown in Fig. 1, 1 is a stiff guide wire supported in a substantially upright position by a base 2. There are two or more thin, substantially equal perforated plates or disc-like members, 3, 4, 5, 6, which may be of steel or other highly elastic material. These plates or discs will slide freely on the guide wire passing through the perforations. The guide wire 1 has a steeply inclined section 12 with a short smooth S curve consisting of a depression 13 and a hump 14, followed by a downward sloping section 30. The steep portion 12 has sufficient length so that the disc may gain the desired velocity in its descent.

The depression 13 will provide a resting station where a disc or plate will rest in stable equilibrium. There is also a section 8 near the upper end of the guide which will hold one or more

2

discs in stable equilibrium ready to be sent down the incline 12. The end of the guide may be formed as a stop 19 to prevent the discs from sliding off the upper end.

After an element 3 is placed in the depression 13, another disc or plate 4 may be released from the upper region 8 in the direction of the incline and will slide down the guide 1 and strike plate or disc 3, which will suddenly take up the motion and slide over the slight hump 14 and on down the guide to the base 2, the disc 4 suddenly stopping in the depression 13 and remaining there. This interchange of motion and position occurs so suddenly that it is difficult for the human eye to sense it—disc or plate 4 appears to go right through disc 3 without sensibly disturbing it. Similarly, additional discs or plates 5, 6, when dropped suddenly, displace the previous ones resting in the depression on the guide, although the appearance is as above indicated. Those conversant with the science of dynamics will recognize that the actions just described clearly demonstrate the laws of conservation of linear momentum and conservation of energy, as applied to the collision of elastic bodies of equal mass. The action described here is uniquely different from collisions between croquet balls, billiard balls, marbles, etc., in that the moving objects or projectiles used in my device are so thin that at the instant of collision the two bodies are so closely contiguous that it is difficult to distinguish their individual identities, whereas croquet balls, marbles, etc., even while colliding, have their centers sufficiently far apart that their separate identities are readily perceived.

I consider it desirable to have the base detachable, for convenience in packing and transporting the device. One way of making the base 40 detachable is to have one or more grooves 15 into which the guide fits snugly. Fig. 2 shows a sectional view of the way the guide may fit into the base 2. The base is grooved around its middle section and the guide bent into an open loop 16 which snugly fits into the groove. The guide wire may have sufficient spring tension so that it may be slid into the grooved base which will hold the guide wire in a rigid position, permitting the action and operation described above.

Obviously, there are many variations of embodiment and operation of this device, e. g.:

The guide may be supported at the eyelet 19 instead of a base as shown in Fig. 2.

The guide may have two or more depressions,

17 and 18 as indicated in Fig. 3, so that successive collisions may occur at such depressions.

The number of discs or projectiles participating in collision is optional—one moving projectile may strike one stationary one, two moving ones may strike one stationary one, one moving one may strike two stationary ones, etc., with characteristic and interesting results.

The projectiles may be set in motion manually or in any suitable manner, and instead of having the discs drop they may be impelled by spring action or in any other way. If the projectiles are set in motion by means other than gravity, then section 12 does not necessarily have to be steeply inclined. In such case, the device may employ double action, if desired. One embodiment of such a variation is shown in Fig. 4, in which the guide 20 is substantially horizontal, but has one or more slight depressions 21. A thin disc 22 resting in equilibrium in a depression 21, when hit by another thin disc 23 propelled against it by release of spring 24, by drawing down latch 25, suddenly takes up the motion of disc 23 which suddenly stops in the depression. Obviously such action may be produced from left to right, or right to left, or alternately.

In the embodiment of Fig. 1, various colors may be used to make the device more attractive, particularly on the discs or plates. The discs may also be varied in size, mass, and shape to show corresponding collision effect, so long as they are thin. The device works more satisfactorily if the guide and discs or projectiles are smooth so as to slide freely.

Having now described my invention, I claim:

1. An amusement device of the character described comprising a smooth guide wire having relatively long portions and a short depressed region therein intermediate the long portions, a base supporting said guide in a substantially upright position with the depression forming a horizontal step, a flat, thin, highly elastic member formed as a disc with a hole therein through which the guide loosely extends, supported freely by said guide in upright position in said depression, a second similar member positioned about said guide at a point above said first member and adapted to be propelled along said guide against said first member, whereby said second member will abruptly stop on contact with the first member and impart its momentum to said first element.

2. An amusement device of the character described comprising a smooth guide wire having a plurality of steeply inclined portions connected by short depressed regions forming substantially horizontal steps, a plurality of flat, thin, highly elastic plate members having perforations through which the guide loosely extends and supported freely in the depressions adapted to be propelled out of said depression when another similar member is permitted to descend freely the steep incline to a depression and impact against said plate member, in said depression and cause it to descend the next incline and strike the member in the next depression for successive and similar reaction.

3. An amusement device of the character described comprising a smooth guide wire having

a plurality of steeply inclined portions connected by short depressed regions forming substantially horizontal steps, a base member having a groove therein for supporting the guide wire in a substantially upright position, a plurality of flat, thin, highly elastic plate members having perforations through which the guide loosely extends and supported freely in the depressions adapted to be propelled out of said depression when another similar member is permitted to descend freely the steep incline to a depression and impact against said plate member, in said depression and cause it to descend the next incline and strike the member in the next depression for successive and similar reaction.

4. An amusement device of the character described comprising a smooth guide wire having a plurality of steeply inclined portions connected by short depressed regions forming substantially horizontal steps, a removable base member having a groove therein for supporting the guide wire in a substantially upright position, a plurality of flat, thin, highly elastic plate members having perforations through which the guide loosely extends and supported freely in the depressions adapted to be propelled out of said depression when one of said members is permitted to descend freely the steep incline to a depression and impact against said plate member, in said depression and cause it to descend the next incline and strike the member in the next depression for successive and similar reaction.

5. An amusement device of the character described comprising a smooth guide wire having a plurality of steeply inclined portions connected by short depressed regions forming substantially horizontal steps, a base member having a groove therein for supporting the guide wire in a substantially upright position, the upper end of said guide wire having a loop, a plurality of flat, thin, highly elastic plate members having perforations through which the guide loosely extends and supported freely in the depressions adapted to be propelled out of said depression when another similar member is permitted to descend the steep incline to a depression and impact against said plate member, in said depression and cause it to descend the next incline and strike the member in the next depression for successive and similar reaction said loop being larger than the perforations, to serve as upper retainer means for the plate members.
